United States Patent Office

Des. 206,903
Patented Feb. 7, 1967

206,903

SERVICE STATION CABINET

Homer F. King, Elmhurst, Ill., assignor to Advertising
Metal Display Co., Chicago, Ill., a corporation of
Illinois

Filed Jan. 24, 1966, Ser. No. 730

Term of patent 14 years

(Cl. D52—2)

Fig. 1

Fig. 2

FIG. 1 is a perspective view taken from the front and one side of a service station cabinet embodying my new design.

FIG. 2 is a front elevational view thereof; and

FIG. 3 is a perspective view taken from the rear and side shown in FIG. 1.

The dominant features of my design reside in the portion shown in full lines.

I claim:

The ornamental design for a service station cabinet, as shown and described.
